UNITED STATES PATENT OFFICE.

EDWIN C. RUTHVEN, OF PHILADELPHIA, PENNSYLVANIA, ASSIGNOR TO
DAVID WOLFE BRUCE, OF NEW YORK, N. Y.

DESIGN FOR PRINTING-TYPE.

SPECIFICATION forming part of Design No. 17,176, dated March 8, 1887.

Application filed December 17, 1886. Serial No. 221,901. Term of patent 14 years.

To all whom it may concern:

Be it known that I, EDWIN C. RUTHVEN, (assignor to DAVID WOLFE BRUCE,) of the city and county of Philadelphia, Pennsylvania, have invented a new Design for a Font of Printing-Type, of which the following is a specification.

The nature of my design is clearly shown in the accompanying typographic impression, to which reference is made; and it consists of an ornamental letter shaded upon the right and below by a heavy line followed by a series of fine inclined light lines. The up-and-down portions of the B, D, E, F, H, I, K, L, M, P, R, T, X, Y, and Q fluted at top and bottom, which feature characterizes the lower portion of the A, the left-hand up-and-down portion of the N and its upper right-hand portion, and the upper portions of the U, V, and W, the faces of all the letters are ornamented by a series of light horizontal lines and the heavy flourishes, as shown.

The character of the design is preserved in the symbol &, the punctuation-marks, notably the interrogation and exclamation points, and in the numerals and the dollar and pound-sterling marks.

Having now described my invention, I claim as new—

The design for a font of printing-types, as shown and described, the same consisting of an ornamental letter shaded on the right and below by a heavy line followed by a series of short inclined lines, the up-and-down portions of the B, D, E, F, H, I, K, L, M, P, R, T, X, Y, and Q fluted at top and bottom, which feature characterizes the lower portion of the A, the left-hand up-and-down portion of the N and its upper right-hand portion, and the upper portions of the U, V, and W, the faces of all the letters ornamented by a series of light horizontal lines and the heavy flourishes, as shown, and the character of the design preserved in the symbol &, the punctuation-marks, notably the interrogation and exclamation points, and in the numerals and dollar and pound-sterling marks.
